(57) CLAIM

The ornamental design for a cosmetic brush cleaning mat, as shown and described.

DESCRIPTION

FIG. 1 is a perspective view of a cosmetic brush cleaning mat showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof;

FIG. 9 is a referential view showing my new design in an unused condition; and,

FIG. 10 is another referential view showing my new design in an unused condition.

The broken lines showing portions of the cosmetic brush cleaning mat form no part of the claimed design.
